UNITED STATES PATENT OFFICE

156,921

DRINKING GLASS

Alexander Sloan, Cumberland, Md.

Application October 25, 1948, Serial No. 149,293

Term of patent 14 years

(Cl. D36—8)

To all whom it may concern:

Be it known that I, Alexander Sloan, a citizen of the United States, residing at Cumberland, in the county of Allegany and State of Maryland, have invented a new, original, and ornamental Design for Drinking Glasses, of which the following is a specification, reference being had to the accompanying drawing, forming part thereof.

I claim:

The ornamental design for a drinking glass, substantially as shown.

ALEXANDER SLOAN.
